UNITED STATES PATENT OFFICE.

EDWARD L. McDONELL, OF MUSKEGON, MICHIGAN.

REFRIGERATOR-CAR.

SPECIFICATION forming part of Letters Patent No. 600,840, dated March 15, 1898.

Application filed November 10, 1896. Serial No. 611,628. (No model.)

To all whom it may concern:

Be it known that I, EDWARD L. McDONELL, a citizen of the United States, residing at Muskegon, in the county of Muskegon and State of Michigan, have invented certain new and useful Improvements in Refrigerator-Cars; and I do hereby declare the following to be a full, clear, and exact description of the invention, such as will enable others skilled in the art to which it appertains to make and use the same.

My invention relates to refrigerator-cars for carrying produce and the like, and has for its object to so construct the same that it may be used as a refrigerator-car in summer without ice and as a warm car in cold weather to prevent the contents from freezing, the arrangement being such that a current of air is caused to circulate entirely around the produce-containing receptacles or bins within the car, and thereby prevent heating or rotting of the material carried therein.

With these objects in view my invention consists in the novel construction, combination, and arrangement of parts and in the various details thereof, as will first be pointed out in the specification and then claimed.

In the drawings forming a part of this specification, and in which like symbols of reference indicate corresponding parts, Figure 1 is a longitudinal section of a car, showing my improvement applied thereto, the side being removed and the bin being exposed and the right end thereof showing the boarding of the bin left off. Fig. 2 is a plan of the same with the roof of the car removed. Fig. 3 is a vertical transverse section of the same. Fig. 4 is a sectional plan view showing the construction applied to a car with double-boarded sides, and Fig. 5 is a vertical section of the construction shown in Fig. 4.

A denotes the top of my improved car; B, the sides; C, the bottom; D, the bin for carrying produce; E, the air-space at the bottom thereof; E', the air-space at the side thereof, and E² a grating connecting the top of the bin with the sides of the car, but permitting the air to pass therethrough.

The inner bin or apartment is made of the best kind of matched lumber, so as to be perfectly air-tight. The space between the bin and floor of the car is generally from about three to four inches, and the air-space be-

tween it and the sides of the car is of a corresponding size. The corners of the bin are cut off, as at α , so as to leave an air-space of greater area than at the sides or bottom. The top of the bin or compartment is left uncovered, leaving the upper part of the car as an air-space.

The result of this construction is that the heat generated from the fruit or vegetables causes the air to rise in the car and creates a general circulation through the air-spaces, thus producing a uniform temperature throughout the car. This prevents the contents from decaying or molding, as they will simply dry out. This result of course obviates the use of ice in warm weather. The same circulation in cold weather prevents the freezing of the contents of the car. The corners are cut off, as before mentioned, for the reason that fruits or vegetables in cars begin to freeze at the forward corners of the car when in motion. By cutting off the corners a large air-space is gained, and this danger is obviated.

It is obvious that as long as there is a variation between the temperature in the air-spaces around the bin and the body of the car a constant circulation will be kept up, the heated air escaping from the air-space, while the colder air in the car will enter the same.

In Figs. 4 and 5 the construction is shown as applied to a car having double boarding with a dead air-space, (represented by b.)

While I have shown my invention in the preferred form, it is evident that many modifications of the same may be made without departing from the spirit of my invention.

Having thus described my invention, what I claim as new, and desire to secure by Letters Patent, is—

In a car of the character described, the combination with the main receptacle contained therein, formed with air-spaces therearound, and the ends of the receptacle cut away on a bevel forming enlarged air-chambers at such points, and the grating connecting the upper edges of the receptacle with the car, substantially as described.

In testimony whereof I affix my signature in presence of two witnesses.

EDWARD L. McDONELL.

Witnesses:

WM. CARPENTER,
ROBT. E. BUNKER.
